PHOTOGRAPHIC MATERIAL

Cyril J. Staud, Rochester, N. Y., assignor to Eastman Kodak Company, Rochester, N. Y., a corporation of New Jersey

Application April 15, 1942, Serial No. 439,007

1 Claim. (Cl. 95—8)

1

This invention relates to a photographic material of the type in which a luminescent layer is positioned between the support and the photographic emulsion and, specifically, it is an improvement over that disclosed in the Patent No. 2,322,038, of Clarence L. A. Wynd and Gerould T. Lane, and is of use in the process of Patent No. 2,322,082 of the same inventors.

In the process therein described, a differentially luminescent image is printed upon a photographic layer beneath which is a fluorescent layer from which it is shielded by a removable opaque layer, so that any rays emitted by the luminescent layer during the exposure of the photographic layer do not also affect it. The image is developed by a process removing the opaque layer and the resulting element contains a photographic image and a fluorescent screen which can be used to impress a differentially luminescent image upon another photographic element.

The present invention relates to a photographic element in which there is no removable opaque screen but which can be used in the same process.

Referring to the accompanying figure, 1 indicates a support, 2 a fluorescent layer thereon and 3 a sensitive photographic emulsion.

The support 1 may be a rigid sheet such as steel, aluminum, plywood or other material, over which is coated a layer 2 containing a material which, when activated by light or X-rays emits rays to which the photographic layer 3 is insensitive. For example, if the layer 3 is an emulsion insensitive to green, the luminescent material in layer 2 may be zinc-ortho-silicate, which when activated by X-rays fluoresces with a maximum at about 525 mu, in the green region of the spectrum.

The process in which this photographic element is used involves the making of a differentially luminescent image the color of the rays from which are of a wave length to which the photographic layer 3 is sensitive. This image may be made by drawing with an opaque lacquer or pencil upon a fluorescent screen; by drawing with a pencil or lacquer containing a fluorescent material upon a non-fluorescent sheet; by scriv- ing or engraving in a fluorescent layer, removing the fluorescent material to form a non-fluorescent line or image; or by any other means forming an image which when activated by light, X-rays or other radiant energy is differentially luminescent. The luminescent material may be calcium tungstate as proposed by Lane and Wynd in their application, Serial No. 407,959, filed August 22, 1941, now Patent No. 2,303,942, granted December 1, 1942, or, preferably barium fluorochloride as described in the copending application of Herbert J. Dietz, Serial No. 437,197, filed April 1, 1942 now Patent No. 2,303,917, granted December 1, 1942. The light emitted from this is in the violet and

ultraviolet region to which ordinary photographic emulsions are highly sensitive.

The sheet carrying the image made as described is placed in contact with my improved photographic element and exposed to X-rays which produce a fluorescent image, with continuing phosphorescence for a time after activation. The luminescent rays impress a developable latent image in the layer 3. The X-rays also excite the luminescent material in the layer 2, but the rays emitted thereby do not affect the layer 3.

After development there remains a silver opaque image in the layer 3. This element is placed in contact with a support carrying a green sensitive photographic layer. When the assembled plates are exposed to X-rays the green luminescent rays from the layer 2 affect the green sensitive layer except where they are intercepted by the opaque silver image.

Since all of the supports are preferably of opaque, nonfrangible material as is necessary when the images are drawings used in making templates or patterns of large size such as are suitable for making large maps and automobile and airplane parts, the final image is positive and also unreversed from right to left with respect to the original luminescent image.

In order to reduce halation, an anti-halation dye may be used in the layer 2. This dye, if not decolorized or removed in the processing bath, should transmit the luminescent light but absorb the light to which the layer 3 is sensitive. Examples of dyes transmitting green and absorbing blue and violet not causing serious desensitization are (1) tartrazine and related pyrazolone dyes (2) simple azo dyes free from nitro or amino groups, such as benzene azo resorcinol or 2-hydroxy-5-1(1-naphthyl azo)-benzaldehyde, or (3) monomethine oxonol dyes, such as bis-[1-sulfophenyl-3-methyl-5-pyrazolone-(4)]-methine oxonol.

The first sheet carrying the image may be exposed to X-rays while out of contact with my improved plate and then at once moved into contact with it, the exposure taking place entirely by phosphorescent light. Since this exposure is of the order of several minutes, there will be no appreciable fogging during the short time required to bring the sheets into contact.

Having thus described my invention, what I claim as new and desire to be secured by Letters Patent of the United States is:

A photographic element comprising a rigid, opaque, non-frangible support, a layer of luminescent material thereon which emits green light when subjected to X-rays and a photographically sensitive layer insensitive to green light over said luminescent layer.

CYRIL J. STAUD.
